UNITED STATES PATENT OFFICE.

GEORGE W. GRISDALE, OF PHILADELPHIA, PENNSYLVANIA, ASSIGNOR TO THE BROWN INSTRUMENT COMPANY, OF PHILADELPHIA, PENNSYLVANIA, A CORPORATION OF PENNSYLVANIA.

RECORDING INSTRUMENT.

Application filed October 31, 1923. Serial No. 671,962.

To all whom it may concern:

Be it known that I, GEORGE W. GRISDALE, a citizen of the United States, and a resident of Philadelphia, county of Philadelphia, State of Pennsylvania, have invented a certain new and useful Improvement in Recording Instruments, of which the following is a specification.

The present invention relates to electrical recording instruments, and more particularly to the multiple recording type, in which a single instrument is arranged to be successively connected to a plurality of circuits each of which includes a heating element, so that the result is a plurality of records on the chart respectively corresponding to the temperatures of the respective heating units of the aforesaid electrical circuits.

Some of the objects of the present invention are to provide an improved electrically operated multiple recording instrument; to provide a multiple recording instrument embodying a clock mechanism arranged to be automatically wound during the electrical operation of the instrument; to provide a depressor bar, for an electrical instrument which is so balanced and operated as to make a clear legible record without damaging any of the delicate parts by impact of the depressor bar, and which is also noiseless in operation; to provide a depressor bar which is automatically caused to function in timed relation with respect to certain operating adjuncts of the instrument; to provide means for equalizing the weight of the depressor bar of an electrical recording instrument; to provide a mechanism including a solenoid for intermittently actuating certain adjuncts of the recording instrument; to provide an automatic contact control device for the circuit of the operating solenoid to cause the solenoid armature to function in a noiseless manner; to provide an automatically operated contact mechanism whereby the supply of current to the instrument is maintained at the minimum for operating purposes; to provide an automatic make and break mechanism for controlling the solenoid of an electrical instrument whereby overheating of the solenoid coils is prevented; to provide a mechanism for intermittently actuating

the recording ink ribbon controlling cam of a recording instrument; and to provide other improvements as will hereinafter appear.

In the accompanying drawings, Fig. 1 represents a side elevation partly broken away of a multiple recording instrument embodying one form of the present invention; Fig. 2 represents a section on line 2-2 of Fig. 1; Fig. 3 represents an elevation on line 3-3 of Fig. 1; Fig. 4 represents a detail on line 4-4 of Fig. 1; Fig. 5 represents a detail on line 5-5 of Fig. 1; Fig. 6 represents a section on line 6-6 of Fig. 5; Fig. 7 represents a section on line 7-7 of Fig. 5; Fig. 8 represents a detail in elevation on line 8-8 of Fig. 1; Fig. 9 represents a section on line 9-9 of Fig. 8; Fig. 10 represents a perspective detail of the circuit making and breaking switch; Fig. 11 represents a detail on line 11-11 of Fig. 2; Fig. 12 represents a side elevation of an intermittent gear for actuating the ribbon control cam; Fig. 13 represents an end elevation of the same; Fig. 14 represents a detail of the current control switch in closed circuit position; Fig. 15 represents a detail of the current control switch in open circuit position; Fig. 16 represents a diagram of the main control circuit.

Referring to the drawings, one form of the invention is shown in the several views in connection with an electrical recording instrument of the multiple recording type; that is, a recording instrument which is arranged to make a plurality of records on a chart or record sheet of a number of temperature conditions existing at a plurality of furnaces or other heating elements, the said records being made one at a time by successive connection of the circuits which transmit the temperature or temperature equivalents. It will be understood, however, that certain features of the invention are equally as well applicable to an electrical recording instrument of the single type; that is, one which is arranged to record the temperature or condition of a single unit only. In the present instance, a recording instrument 10 is shown, of the galvanometer type, the movable system of which carries a pointer 11, which is arranged to travel in a path parallel to and in close proximity to a record or chart sheet 12, which is continuously

fed in any well-known manner. In this type of instrument, the record is made upon the chart 12 by means of a colored ribbon 13, which is fed between the pointer 11 and the chart 12, and impresses a dot or other symbol upon the chart by impact of the pointer 11 upon the ribbon. In the present instance, the ribbon 13 is of the multi-colored type, having one color to represent each furnace or heating element, or a combination of different colors of the ribbon as an identifying characteristic for a particular unit, such, for example, as fully set forth in co-pending application, Serial No. 15 657,245. The impression or impact means consists of a depressor bar 14, which is periodically operated to strike the pointer and thus, through the ribbon, make the desired impression upon the chart or record sheet.

20 For the purpose of actuating the depressor bar 14, and causing it to deliver an effective blow to the pointer without, however, damaging the pointer or producing an audible sound, the said bar 14 has its side arms 25 pivoted adjacent their rear ends to a suitable fixed part of the instrument frame, as shown at 15, so that the major portion of the weight of the depressor bar is toward the front of the instrument, and 30 normally tends to fall by gravity toward the chart sheet 12. To one side of the depressor bar and in front of the fulcrum 15, a link 16 is pivotally connected, and joins at its other end a crank arm 17 fast to a 35 spindle or rock shaft 18, which is suitably journalled in the side walls of a casing 20, this latter serving, as will later appear, to contain the controlling and actuating mechanism for certain parts of the apparatus.

40 In order to periodically rock the spindle 18 to cause the depressor bar 14 to be raised preliminarily to making its impression stroke, the spindle 18 has rigidly secured to it an arm 21, from the end of which an actuating 45 bar 22 is suspended. The latter terminates at its lower end in an irregular-shaped head 23, formed at one side with a V tooth 24 and at the other side with a laterally and downwardly inclined face 25. The tooth 50 24 is arranged to mesh with the respective teeth of a cam 26, and the head 23 is normally held pressed into meshing engagement with the said gear by contact of the inclined face 25 with a rotatably adjustable 55 post 27 fast to the casing 20. The cam 26 is driven from a main clock mechanism 28 of any well-known type, and is geared to move at a predetermined speed so timed as to cause the actuating bar 22 to raise the depressor bar 14 periodically at definite time 60 intervals. As shown in Fig. 1, the cam 26 rotates in a counter-clockwise direction, so that as its teeth pick up the tooth 24, the head 23 receives an intermittent movement, and rides up by the lateral pressure of the inclined face 25 upon the post 27 to transmit 65 rocking motion to the spindle 18. At the end of each upward movement, the tooth 24 is forced out of mesh with the cam 26, and consequently the weight of the depressor bar 70 overbalances the actuating bar 22 and its parts, and thus not only makes its impression stroke but also drops the head 23 to bring the tooth 24 into mesh with the next succeeding tooth of the cam 26. The adjustable post 27 and cam-like face 25 serve to give the required lateral movement to the head under the action of the cam 26 and also distributes the weight of the parts so that excessive pressure on the gear is removed.

75 For the purpose of more perfectly balancing the depressor bar 14 and providing means whereby the adjustment of its working stroke can be varied, a coiled spring 30 80 (Figs. 2 and 11) is provided, having one end fast to a lug 31 of the casing 20 and its opposite end coiled about the spindle 18 and made fast thereto in any desired manner. The coiling of this spring 30 is in the proper direction to normally place a nicely adjusted tension upon the spindle 18, which acts opposite to the weight of the depressor bar 85 so that the impact of the bar is just sufficient to make a clear, legible impression upon the 90 chart, while noise and damage to the delicate parts is avoided by the cushioning effect of the spring.

95 While the clock mechanism 28 forms no specific part of the invention, and may be 100 of any well-known type, one feature of the invention relates to the automatic winding of the main spring 32 of the clock mechanism, whereby it is maintained operative under all running conditions of the recorder. 105 To that end, the staff 33 of the main spring 32 carries a ratchet 34 (Figs. 8 and 9) arranged to be engaged by a spring pressed pawl 35 pivoted to a gear 36 loosely mounted on the staff 33 and in mesh with a pinion 37 (Figs. 1 and 3) on a counter-staff 38. This last carries a gear 39 fast thereon in mesh with a pinion 40, loosely mounted upon a driving spindle 41 but fast to a rotatable 110 casing 42 which is arranged to be driven by a coil spring 43, the outer end of which is fast to the casing 42 and its inner end fast to the driving spindle 41 (see Fig. 6). In order to transmit motion to the spindle 41, a ratchet 44 (Fig. 7) is keyed or otherwise made fast to the spindle 41, and is arranged to be given a step by step movement by means of a spring pressed pawl 45 pivoted to a disc 46, which is fast to a gear 47, the latter being loosely mounted upon the spindle 41. An intermittent movement is imparted to the gear 47 through the medium of a gear segment 48 (Fig. 1) fixed to a shaft 49, which also has keyed thereon a second gear segment 50 in mesh with a rack 115 120 125 130

51 formed on an extension 52 of the armature 53 of a double solenoid 54. The circuit control for the solenoid 54 will be later described.

5 From the foregoing, it will be evident that when the solenoid 54 is energized and draws its armature 53 upwardly, as shown in the drawings, the rack 51 will transmit a counter-clockwise movement to the shaft 49
 10 by means of the gear segment 50, and thus, by gear segment 47 impart a partial rotation to the disc 46 and pawl 45, whereby the ratchet 44 transmits the same movement to the spindle 41, which in turn winds the coil
 15 spring 43. In consequence, the uncoiling of the spring 43 transmits motion by way of the pinion 40, gear 39, counter-staff 38, pinion 37, gear 36, to the staff 33, which results in a winding of the main spring 32
 20 of the clock mechanism 28, through the pawl 35 and ratchet 34.

For starting purposes, the main clock spring 32 can be manually wound because the staff 33 of the main spring 32 extends
 25 exterior of the casing 20 and may be operated by a knurled head or like means.

The intermittent rocking motion of the gear segment 48 and its shaft 49 is also utilized to impart a step by step motion to
 30 the other units of the recording instrument, and in this instance an additional use is to cause an intermittent rotation of a multiple switch 55 (Fig. 3) by which the thermocouple circuits or other plurality of electrical circuits are connected one at a time to the instrument. The switch 55 referred to is fully described in applicant's copending application, Serial No. 671,961, and it is therefore deemed unnecessary to explain
 35 the details thereof, since only the step by step movement is here concerned. For this purpose, the ratchet 45 of the spindle 41 is fastened to a gear 56, which is in mesh with a gear 57 fast to the hollow spindle 58 and
 40 by that clutched to the rotary member of the multiple switch 55. Another use of this step by step movement is to actuate a cam 60, which serves to shift the ribbon carriage and position it for the making of different
 45 combinations of color records, such mechanism being fully described in applicant's copending application, Serial No. 657,245. In the present construction, the cam 60 is provided with a plurality of equally spaced
 50 laterally projecting pins 61, which are located in the path of movement of an escapement element 62 fast to a spindle 63 which has a gear 64 keyed thereon in mesh with a gear 650 upon the shaft 49.

60 The element 62 is provided with two oppositely arranged inwardly turned teeth 65 and 66, the opposite inner faces of which are of curved cam form to engage and cause the respective pins 61 to be moved through
 65 a definite arc of travel whenever the element

62 is oscillated. Thus, when the element 62 is rocked about its axis 63, the tooth 65 is removed from engagement with and out of the path of one of the pins 61 which it normally engages, and the other tooth 66 during this same movement picks up the succeeding pin 61 and advances it through the predetermined arc to shift the cam 60 the required distance to have it carry out its ribbon changing function. Upon the reverse rocking movement of the element 62, the tooth 65 will ride into the path of the pin 61 which has just been moved, while the tooth 66 will swing back to a position beneath the next succeeding pin 61 so that when it is again rocked it will engage that pin and produce another feeding step to the cam 60.

For the purpose of periodically energizing the operating solenoid 54, the two coils thereof are connected in parallel by conductors 70 and 71 (Fig. 16) with the leads 72 and 73, which are respectively connected to the terminals 74 and 75 from the source of current supply, though the lead 72 includes in series with it a make and break switch 76 to automatically control the solenoid circuit. This switch 76 comprises a strip 80 (Figs. 1, 14 and 15) of flexible conducting material mounted in an insulating block 81, which also carries a second flexible conducting strip 82 spaced from the strip 80 and in general parallel relation thereto. The strip 80 is provided with a contact 83 and the strip 82 is similarly provided with a contact 84, the two contacts 83 and 84 being arranged in juxtaposed relation and in relatively close proximity to each other but normally spaced apart so that there is no electric connection between the strip 80 and the strip 82. As a means for making contact between the two points 83 and 84, the strip 80 terminates in an extension finger 85 which is bent downwardly and outwardly, while the strip 82 terminates in a finger 86, bent upwardly and outwardly, the two fingers 85 and 86 lying respectively in different vertical planes so that both are free to move up or down without interference or making contact one with the other.

It will be noted that the finger 85 is longer than the finger 86, for a purpose to be presently explained, and both fingers are arranged in the path of a cam 87 upon a shaft 88, suitably driven from the clock mechanism 28 at a predetermined speed of rotation. In this instance, the cam is provided with two shoulders 90 and 91 at diametrically opposite points, so that the switch 76 functions twice for each rotation of the cam 87. Except for brief instants immediately subsequent to the passage of the cam shoulders 90 and 91 past the end of the switch finger 86, the two fingers 85 and 86 rest upon the face of the cam and are so shaped

that the cam then deflects the switch finger 86 sufficiently to hold the contact 84 out of engagement with the contact 83. As soon, however, as the cam 87 rotates to a place 5 where the shoulder 90, for example, passes the shorter finger 86, the latter will snap from the high point of the cam to the low part, as shown in Fig. 14, and bring the contact 84 into contact with the contact 83 to close the circuit, which thus causes energization of the solenoids 54. The solenoid energizing circuit closed in the manner just described is opened again as soon as the longer switch finger 85 is permitted to snap off the corresponding cam shoulder, (90 in the example given). The time required for the relative movement of the cam 87 and switch finger 85 necessary to permit the latter to snap off a cam shoulder and re-open 10 the solenoid energizing circuit is shortened, as will shortly be described, by the bodily movement given to the conducting strips 80 and 82 when the solenoids 54 are energized. 15 As soon as the solenoid is energized sufficiently to cause the armature 53 to properly actuate the parts controlled by its movement, it is desirable to break the circuit in order not only to prevent the armature completing its stroke with an undesirable blow with 20 its attendant noise and possible damage to delicate parts but also to prevent overheating of the solenoid coils as well as waste of current. To that end, the insulating block 81 of the switch 76 is fast to an arm 92 of 25 a pivoted lever 93, the movement of which is guided by a pin 94 fast to a suitable fixed part, and extending through a slot 95 in the arm 92. Movement is transmitted to the arm 92 by means of a trip arm 96 which is connected at its upper end to the arm 92, while 30 its opposite end is freely suspended and has a laterally projecting extension 97 (Fig. 2) which passes through the casing 20 and into the path of movement of a trip 98 in threaded engagement with a supporting piece 99 35 fixed to the armature 53. The threaded connection of the trip 98 serves to adjust its position with respect to the arm extension 97, so that the time of operation of the trip 96 40 can be varied as required to break the circuit at the end of the desired contact period. It will thus be seen that when the cam 87 reaches the point in its revolution where either the shoulder 90 or the shoulder 91 releases the finger 86, the circuit will be closed by contact of the points 83 and 84, and the solenoid 54 energized. This results in the desired movement of the armature 53 but prior 45 to the completion of its stroke, and after proper rocking of the segment 50, the trip 98 picks up the extension 97 and thus transmits a movement to the arms 96 and 92 which shifts the switch 76 and causes the longer finger 85 to spring off of the cam shoulder to 50 break the circuit at the contacts 83 and 84.

It has been found that closing the circuit of the solenoid 54 for approximately one-twentieth of a second supplies sufficient current to cause the solenoid to operate its armature 53 and transmit the necessary 55 movements to the other parts which are to be intermittently actuated to carry out the several operations intended. This shortening of the time the circuit is closed plays a very important part in the practical operation of the instrument, because it means not only a saving of current but also a diminution of the pull upon the armature 53 at just the proper point in its stroke to damp its movement, and thus prevent violent impact with the solenoid. As heretofore stated, the shortening of the time in which current flows through the solenoid 54 eliminates the danger of overheating the coils. 60

In order to absorb the shock produced by the armature 53, when it falls by gravity, upon deenergization of the solenoid, a shock absorbing element 100 (Figs. 1 and 2) in the form of a cushion of rubber or other suitable yielding means is located in the path of the plunger extension 51, being supported by a fixed plate 101 secured to the casing 20, and so located as to be struck by the plunger 51 at substantially the end of its downward stroke. 65

The operation of the instrument is as follows: The recorder of the present invention is arranged to be operated both mechanically and electrically, the mechanical movement being produced by a suitable clock mechanism 28, which has the function of feeding the chart paper 12, actuating the cam for controlling the opening and closing of the electrical circuit, and operating the depressor which functions with the pointer 11 to make an impression by means of the ribbon 13 upon the paper 12. The electrical mechanism is in the form of a periodically operated solenoid which serves to automatically maintain the clock mechanism in 100 wound condition, to control the shifting of the recording ribbon from one position to another for producing different colored identifying characteristics upon the chart 12, and to impart a step by step movement 105 to the multiple switch which successively connects the various circuits of the thermocouples to the instrument. 110

The energization of the solenoid 54 is controlled by the make and break switch 76 under the action of the continuously rotating cam 87, the two fingers 85 and 86 of the switch member being normally in rest position upon the low portion of the cam to maintain the contacts 83 and 84 separated and the circuit open. When the high point of the cam is reached, both fingers of the cam still ride over it without altering the spaced relation between the contacts 83 and 84, but as soon as the shorter finger 86 120

drops from the cam by way of either the shoulder 90 or 91, then the contact 84 engages the contact 83 and closes the circuit including the solenoid 54. The energization of the solenoid 54 causes the armature 53 to be drawn upwardly, to thereby transmit motion from the rack 51 to segment 50, and from segment 50 by way of shaft 49 to segment 48, which imparts a partial rotation to the chain of gears to wind the spring 43, which, in turn, produces a winding movement to the main clock spring 32. Simultaneously, the rocking movement of the shaft 49 causes the escapement 62 to rock, so that one of the pins 61 of the cam 60 is released, and is actuated and moved through a definite predetermined arc sufficient to produce the desired rotation of the cam for the purpose intended. Also the rock motion of the shaft 49 is transmitted by way of gears 56 and 57 to the rotatable element of the switch 55, which is thereupon shifted to a different position in order to connect a different circuit with the recording instrument. As soon as the armature 53 has reached the required point in its stroke to insure the foregoing motion to the parts controlled by it, the trip 98 strikes the finger 97, and causes the arm 96 to shift the switch 76, so that the long finger 85 thereof snaps from the high point of the switch sooner than it otherwise would, and thus breaks the circuit at the proper time in the cycle to cut off the current from the solenoid after the latter has completed its work. As soon as the solenoid 54 is deenergized, the plunger 53 drops back by gravity, the impact thereof being cushioned by the member 100 and the parts assume their former position preparatory to the next intermittent movement. During the foregoing electrically operated steps, the clock mechanism is transmitting motion to the cam 26, and turns it in a direction to lift the head 23, link 22, and by means of the crank arms 21, 17, shaft 18 and link 16, gradually raise the depressor 14 preliminary to making a record. The upward movement of the head 23 is accompanied by a laterally swinging movement, due to the power applied by the cam 26 and the inclined cam face 25 sliding upon the pin 27, so that at the required point in the rotation of the cam 26 and with definite relation to the position of the other parts of the instrument, the head 23 automatically disconnects from the cam 26, and as the movement of the latter continues drops back to its former position, but it then enters in the next succeeding space between the teeth of the cam 26. This releasing of the head 23 relieves the depressor bar 14 of the force acting counter to its weight, and it thereupon falls to strike the pointer 11 with just sufficient force to make a sharp im-

pression upon the chart 12 by means of the ribbon 13. By varying the tension of the spring 30, the relative weights of the depressor and its actuating parts can be adjusted to a nicety and the depressor be thus caused to fall noiselessly and without damage to any of the parts. Furthermore, by supporting the link 22 and its connected parts upon the post 27, a considerable portion of its weight is removed from the cam 26, and thus relieves the clock mechanism from the total pressure due to the weight of these parts.

Although only a single form is shown in which this invention may be embodied, it is to be understood that the invention is not limited to any specific construction, but might be applied in various forms without departing from the spirit of the invention or the scope of the appended claims.

Having thus described my invention, I claim:

1. In a recording instrument, the combination with a deflecting pointer, of means for intermittently depressing said pointer comprising a rotating peripherally notched cam, a member having a tooth engaging the periphery of said cam, guiding means for a portion of said member adjacent said tooth compelling the latter to move tangentially as well as radially of said cam as it enters and leaves a peripheral notch of the latter, and guiding means for a portion of said member remote from said tooth constraining said last mentioned portion to movement along a path approximately parallel to the tangential movement of said tooth.

2. In a recording instrument, the combination with a deflecting pointer, of means for intermittently depressing said pointer comprising a rotating peripherally notched cam, a movable guide, a member pivotally suspended from said guide and formed with a tooth engaging the periphery of said cam, and guiding means for a lower portion of said member compelling said tooth to move tangentially as well as radially of said cam as it enters and leaves a peripheral notch of the latter.

3. In a recording instrument, the combination of an index member, a rock shaft, a depressor connected to said rock shaft to engage and disengage said index member as the rock shaft is turned in one direction or the other, a crank arm connected to the rock shaft, a rotating peripherally notched cam, a member pivotally connected to and suspended from said crank arm and formed with a lateral tooth adjacent the periphery of said cam at the upmoving side of the latter, and guiding means for said suspended member forcing the tooth of the latter to move toward the cam on a downward movement of the member to carry said tooth into an adjacent cam notch, and limiting the

movement of the tooth away from the cam as said suspended member is moved upward.

4. In a recording instrument, the combination of an index member, a depressor bar arranged to drop by gravity to depress said index member, a step by step mechanism for periodically operating said depressor bar, including means for automatically releasing said mechanism from said depressor bar, 10 and for retarding the fall of said depressor bar.

5. In a recording instrument, the combination of an index member, a depressor bar arranged to drop by gravity to depress said index member, a step by step mechanism for periodically raising said depressor bar, means for automatically releasing said mechanism from said depressor bar, means for retarding the fall of said depressor bar, 20 and adjustable means for varying the impact of said depressor bar with said index member.

6. In a recording instrument, the combination of an index member, a depressor bar pivotally mounted to drop by gravity to depress said index member, a rock lever mechanism connected to said depressor bar to raise said bar, a head pivoted to said rocking mechanism and having an inclined face 30 at one side and a gear tooth at the opposite side, an adjustable support engaging said inclined face, and a cam having teeth successively engaging said head tooth whereby said head is periodically elevated to actuate 35 said rocking mechanism.

7. In a recording instrument, the combination of an index member, a depressor bar pivotally mounted to drop by gravity to depress said index member, and means including a pivotally suspended head for periodically raising said depressor bar.

8. In a recording instrument, the combination of an index member, a depressor bar pivotally mounted to drop by gravity to depress said index member, and means for periodically raising said depressor bar comprising a rotatable cam, a member actuated by said cam, and guiding means for causing said member to move bodily in a direction 50 generally tangential to said cam on each actuation of the member by the cam.

9. In a recording instrument, the combination of an index member, a depressor bar pivotally mounted to drop by gravity to depress said index member, means including a pivotally mounted head and a rotatable cam coacting therewith for periodically raising said depressor bar, and means for supporting said head on the side opposite to said 55 cam.

10. In a recording instrument, the combination of an index member, a depressor bar pivotally mounted to drop by gravity to depress said index member, a rock lever mechanism connected to said depressor bar to raise 60

said bar, a head pivoted to said rocking mechanism and having an inclined lower face, a fixed member engaging said inclined face to support said head at one side, and means including a rotatable cam for periodically raising said head and causing it to move out of mesh with said cam whereby said depressor bar is released to fall by gravity.

11. In a recording instrument, the combination of an index member, a depressor bar pivotally mounted to drop by gravity to depress said index member, a rock lever mechanism connected to said depressor bar to raise said bar, a head pivoted to said rocking mechanism and having an inclined lower face, a fixed member engaging said inclined face to support said head at one side, means including a rotatable cam for periodically raising said head and causing it to move out of mesh with said cam whereby said depressor bar is released to fall by gravity, and means for adjustably controlling the counterbalancing of said depressor bar.

12. In a recording instrument, the combination of an index member and a depressor, of actuating means for the depressor comprising a rotating gear wheel having flattened teeth, a member, a connection between said member and depressor comprising a pivotal suspension for said member located above the gear wheel, said member being formed with a tooth at the upmoving side of the gear wheel adapted to enter the spaces 100 between the gear wheel teeth, and guiding means for the depending end of the member for causing the latter to be moved tangentially of the gear wheel when its tooth is entered in one of said spaces to thereby impart motion to the depressor and permitting a regulated movement of the member radially of the gear wheel to clear the teeth of the latter after a definite tangential movement, and for causing a return radial movement of the member when the continued movement of the gear wheel permits the tooth thereof to enter a succeeding one of 105 said spaces.

13. In a recording instrument, the combination of an index member, a depressor, a rotating cam formed with peripheral notches, a member having a tooth movable radially of said cam to enter and leave the notches thereof and moved by the cam tangentially 120 of the latter while received in a notch thereof to thereby move said depressor in one direction, and having a tendency to move tangentially of the cam in the opposite direction, and guiding means for said member 125 compelling said tooth to share in a limited tangential movement of the cam when entered in any notch thereof before moving radially out of the notch and compelling the tooth after leaving one cam notch and while 130

making a return tangential movement to move radially inward and enter a following cam notch.

14. In a recording instrument, the combination with an index member, of cooperating depressor mechanism comprising a rock shaft, a depressor connected to said rock shaft and moved to engage and disengage said member as the rock shaft is turned 10 in one direction or another, a crank arm connected to the rock shaft, a member pivotally connected to and suspended from said crank arm and provided with a lateral projection from its depending portion, a rotat- 15 ing cam formed with peripheral notches into which said projection is adapted to enter, said mechanism being loaded with a tendency to move said projection tangentially of said cam in a direction opposite to the 20 projection, and guiding means for the depending portion of said member causing said projection to move radially inward with respect to the cam to enter an adjacent cam notch as the projection moves tangentially 25 of the cam under its loading tendency, and compelling the projection to share a limited tangential movement of the adjacent portion of the cam after being entered in a notch thereof before moving radially out 30 of the notch.

15. In a recording instrument, the combination of a recording mechanism including a chart, a colored impression ribbon, a pointer, electrical means for controlling 35 said pointer, and a depressor bar, means including a clock mechanism for actuating said depressor bar, said chart and the feeding of said ribbon, a winding device for said clock, a rotatable switch for separately 40 connecting electrical circuits to said pointer controlling means, a cam for varying the position of said ribbon relative to said chart, and means including a solenoid for separate-

ly actuating said winding means, said ribbon cam and said rotatable switch in timed 45 relation.

16. In a recording instrument, the combination of a recording mechanism including a chart, a colored impression ribbon, a pointer, electrical means for controlling said pointer, and a depressor bar, means including a clock mechanism for actuating said depressor bar, said chart and the feeding of said ribbon, a cam for varying the position of said ribbon relative to said chart, 50 a plurality of pins projecting laterally from said cam, an escapement arranged to coact with said pins, and means including a solenoid for actuating said escapement. 55

17. In a recording instrument, the combination of a recording mechanism including a chart, a colored impression ribbon, a pointer, electrical means for controlling said pointer, and a depressor bar, means including a clock mechanism for actuating 60 said depressor bar, said chart and the feeding of said ribbon, a winding device for said clock, and means including a solenoid for intermittently winding said wind- 65 ing mechanism. 70

18. In a recording instrument, the combination of a recording mechanism including a chart, a colored impression ribbon, a pointer, electrical means for controlling said pointer, and a depressor bar, means including a clock mechanism for actuating said depressor bar, said chart and the feeding of said ribbon, a rotatable switch for separately connecting electrical circuits to said pointer controlling means, and means 75 including a solenoid for intermittently operating said switch. 80

Signed at Philadelphia, in the county of Philadelphia, State of Pennsylvania, this 11th day of October, 1923.

GEORGE W. GRISDALE.
